(57) **CLAIM**

The ornamental design for a display screen with graphical user interface, as shown and described.

DESCRIPTION

The FIGURE is a front view of a display screen with graphical user interface showing the new design.

The broken lines within the graphical user interface represent portions that form no part of the claim. The outer broken line boundary of the claimed design is congruent with the broken line display screen that forms no part of the claim.

1 Claim, 1 Drawing Sheet
